UNITED STATES PATENT OFFICE

CARL R. HENNICK, OF CLEVELAND, OHIO

HOOD FASTENER

Application filed September 9, 1930. Serial No. 480,640.

My invention relates particularly to hood fasteners for automobiles although, in its broader aspects, the invention pertains to a fastener for any type of closure.

In the past, it has been customary to secure the engine hoods of motor vehicles in their lowered or closed position by means of fastening members pivoted to the vehicle frame and having a spring-urged hook for engaging a lug on the hood. This construction is objectionable for a number of reasons. In the first place, the appearance of the vehicle is marred by the attachment of the hood fasteners to the outside of the body where they are plainly visible. Another objection is that such fasteners make it difficult to clean the hood. The general practice is to provide a polished or plated surface for the hood fastener, which makes its construction somewhat expensive. A further objection is that the working parts of the fastener are exposed to the weather, and subject to rapid deterioration for that reason. In addition, all hood fasteners with which I am familiar are characterized by considerable difficulty in operation.

The present invention has for its objects to eliminate the foregoing objections to known types of hood fasteners. I provide a hood fastener which is located inside or under the hood, so that all the working parts, with the exception of a single operating handle, are concealed from view. This construction considerably improves the appearance of the engine hood, and facilitates cleaning the latter. Since only the operating handle projects from the hood, it is not essential that the other parts be polished or plated. The cost of manufacture is thus reduced. Other advantages of the invention reside in the fact that it is very easily operated by means of the pivoted operating handle and, at the same time, may be securely locked in the closed position. All the working parts, furthermore, with the exception of the operating handle, are protected from the weather, since they are enclosed by the hood, so that long life and satisfactory operation of the device is insured.

In accordance with the invention, I secure

a bracket on the inside of the engine hood for slidably supporting a vertically reciprocable hook. An eye plate, secured to a fixed member of the vehicle frame or chassis, receives the hook to secure the hood in closed position. I employ a compression spring for resiliently urging the hook towards its operative position. For withdrawing the hook and for compressing the spring, I employ a toggle mechanism having an operating handle projecting outwardly from the hood. This mechanism permits the fastener to be operated with very slight effort.

For a complete understanding of the invention, reference should be made to the accompanying drawing illustrating a present preferred embodiment of the invention, although it is to be understood that the drawing is illustrative only, since other constructions embodying the invention may be resorted to within the scope of the broader claims.

In the drawing,

Figure 1 is a front elevation of the invention separated from the engine hood with which it is adapted to cooperate;

Figure 2 is a side elevation of the invention, showing the cooperating portions of the engine hood and vehicle frame in chain lines;

Figure 3 is a side elevation of the engine hood with the operating handle of the fastener projecting therethrough;

Figure 4 is a sectional view along the line IV-IV of Figure 1; and

Figure 5 is a perspective view of a detail.

Referring specifically to the drawing, the invention comprises a bracket or frame member 10. The bracket 10 is adapted to be secured to the inside of an engine hood indicated at 11 by means of rivets or bolts. The bracket is perforated at 12 for this purpose. Adjacent its lower end, the bracket 10 is recessed at 13, and a hollow boss 14, projecting outwardly from the plane of the bracket is formed thereon. This boss is adapted to project through an opening 15 formed in the hood 11.

The ends of the bracket 10 are flanged over at 16, and the flanged ends are provided with square holes 17 for the reception

of a square rod 18. The rod 18 is adapted to slide vertically in the bracket 10, and has its lower end turned up at 19 to form a hook. An eye plate 20, having an opening 21, is secured to the frame 22 of the vehicle. A portion of the metal punched from the opening 21 is bent upwardly at 23 so that a somewhat rounded surface is provided for engagement with the hook 19. The eye plate 20 thus serves as a receiver or holder for the hook 19.

The rod 18 is provided adjacent its upper end with a pair of lateral slots 24 for receiving a U-shaped clip 25. A square washer 26, having an upturned lip 27 is carried by the rod below the clip 25. A coil spring 28 surrounds the rod 18 below the washer 26 and at its lower end is supported by a spring carriage 29. The spring carriage, as shown in Figure 5, is a metal strip formed into a rectangle having square holes 30 in its ends for receiving the rod 18. In addition, an eye 31 is formed integrally with the carriage 29 at one end.

The spring 28, being compressed between the bottom of the carriage 29 and the washer 27, urges the latter against the clip 25 to prevent its removal from the slots 24 in the rod 18.

A yoke 32 traverses the eye 31 in the carriage 29. A fork 33 having an outwardly extending handle is pivoted in the boss 14 on a pin 35 and cooperates with the yoke 32 to form a toggle linkage. By means of this linkage, the spring 28 may be compressed or released to actuate the rod 18 and its hook 19.

In describing the operation, it will be assumed first that the parts have the position indicated in solid lines. The handle 34 is depressed and the toggle linkage 32-33 is in its extending position. This causes the carriage 29 to be raised and the spring 28 to be compressed. The spring 28, through the washer 27 and clip 25, resiliently urges the rod 18 upward, so that the hook 19 engages the eye plate 20 and draws the hood 11 downwardly and inwardly to its closed position. If it is now desired to raise the hood, it is only necessary to pull the handle 34 outwardly to the dotted position 36. As is customary with the present type of fastener, I propose to employ two fasteners on each side of the hood. When the handle 34 has been retracted to the position 36, the toggle linkage 32-33 will have collapsed partially and the carriage 29 lowered to the dotted position 37. In this position of the parts, the spring exerts no upward pressure on the rod 18 and the top of the carriage 29 engages the clip 25. Although the hook 19 remains in the position indicated in solid lines, the hood 11 may be pulled away from the eye plate 20, whereupon the engagement of the curved portion 23 with the hook 19 will force it

downward to the disengaged position. If desired, however, further upward movement of the handle 34 from the position 36 toward the position 38 will result in a positive lowering of the hook 19, by reason of the positive engagement of the top of the carriage 29 with the clip 25. When the hook is lowered to the dotted position 39, the hood may, of course, be withdrawn laterally and lifted with very little effort. The hooks 19, having been disengaged from the eye plates 20, the hood 11 may now be conveniently raised by lifting the handles 34.

When it is desired to replace the hood and lock it into position, it is lowered and moved inwardly so that the hooks 19, occupying the position 39, enter the openings 21 in the eye plates 20. When the hooks have been thus positioned, the handles 34 are pressed down until they occupy the position shown in solid lines. This movement of the handle 34 compresses the spring 28 by raising the carriage 29. The compression of the spring 28 raises the rod 18 and draws the hook 19 into firm engagement with the curved portion 23 of the eye plate 20, so that the hood 11 is drawn tightly against the vehicle frame. As the toggle linkage 32-33 is forced home to its extended position, all the parts are locked against movement until the handles 34 are again retracted.

It will be obvious from the foregoing description that the invention constitutes a distinct improvement over the outside type of hood fastener known heretofore. As already pointed out specifically, the appearance of the hood is improved by placing the operating parts on the inside thereof, and protection from the weather is likewise afforded such parts. The ease of operation characterizing the invention is another advantage which will be apparent. The operator of the fastener need only exert a light downward or upward pressure on the handle 34 to engage or disengage the hook 19. This is a great improvement over the present type in which it is necessary that the operator lean over the fender of the vehicle and exert a considerable effort to raise the fasteners to the position in which they engage the lugs on the hood.

By lengthening the handle 34, the lever arm may be increased so that a very small effort is required to operate the fastener. The long travel of the rod insures easy engagement of the hook 19 with the eye plate 20 at all times, even though the normal separation of these parts is increased as, for example, by a distortion of the vehicle frame in case it is standing on an angle. The angle which the hook 19 makes with the rod 18 is also important. The acute angle between the hook and the rod causes the hood to be pulled in tightly against the vehicle frame and thus preventing rattle. The toggle link-

age for actuating the hook-operated spring permits the latter to be locked in the closed position against all possibility of accidental disengagement as a result of shock or vibration. At the same time, the operating handle, as previously indicated, permits the linkage to be operated with a minimum of effort. The only opening which is required to be made in the hood is practically filled by the 10 operating handle passing therethrough, and a neat appearing construction is thus provided.

Although I have illustrated and described but a single present preferred embodiment 15 of the invention, it is obvious that numerous details of construction may be altered for convenience. The rod 18, for example, may be round in section with a key or guide on the bracket 10 to prevent it from turning. 20 Instead of providing the rod 18 with the hook 19 for securing the eye plate to the frame, this relation may be reversed by providing a hook on the frame and securing an eye to the lower end of the rod 18. The described 25 construction combines economy of manufacture with neat appearance, and is preferred for that reason, but any changes therein may be made without departing from the spirit of the invention as set forth in the following 30 claims.

I claim:

1. A hood fastener comprising an eye-plate, a hook rod for engaging said eye-plate, a bracket for slidably supporting the hook 35 rod, a spring surrounding the rod, a spring carriage slidable on said rod, and a toggle linkage pivoted to the bracket and carriage for compressing the spring to operate the hook rod.

40 2. In a hood fastener, a bracket, a hook rod slidable therein having an end portion adapted to enter an eye, a spring on said rod, a spring carriage slidable on the rod, and a toggle linkage pivoted to the carriage and the 45 bracket.

3. A hood fastener comprising a bracket, a handle pivoted thereon having a projecting fork, a hook rod slidable in the bracket, a spring surrounding the rod, spring engag- 50 ing means slidable on said rod, and a link pivoted to said means and said fork forming a toggle linkage for operating said rod.

4. A hood holder comprising a plate having portions for slidably receiving a hook rod, a spring surrounding said rod, spring engaging means slidable on the rod, an operating handle pivoted on said plate, and a link connecting said operating handle and said spring engaging means, forming a toggle 60 linkage.

5. A hood fastener comprising a plate, an operating handle pivotally supported thereon in bearing lugs struck out from said plate, said handle having a bifurcated fork portion, a hook rod slidable relative to said plate

between the handle bifurcations, a spring on the rod, spring engaging means slidable on the rod, and a yoke connecting said spring-engaging means and said bifurcations.

6. A hood holder comprising a plate, portions of the plate forming guides, a hook rod 70 slidable therein, and hook actuating means including a pivoted lever, a yoke forming a toggle linkage therewith, and means engaged by said yoke for resiliently actuating the 75 hook rod.

7. In a hood fastener, the combination with a base plate, a hook rod slidable therein, a toggle linkage pivoted on said plate, and means for resiliently actuating said rod connected to said linkage. 80

8. In a hood holder, a plate, a hook rod 85 slidable thereon, a toggle linkage for operating said hook rod, comprising a member pivoted on said plate and projecting therethrough, a second member pivotally connected to said first-mentioned member, and a resilient spring-actuating means on said rod, having a pivotal connection with said second member. 90

In testimony whereof I have hereunto set my hand.

CARL R. HENNICKE.
